UNITED STATES PATENT OFFICE.

BERNARD STAUB, OF NEW YORK, N. Y.

FIRE AND BURGLAR ALARM.

No. 856,924.

Specification of Letters Patent.

Patented June 11, 1907.

Application filed September 14, 1906. Serial No. 334,689.

To all whom it may concern:

Be it known that I, BERNARD STAUB, a citizen of the Austrian Empire, and resident of the borough of Brooklyn, city of New York, in the county of Kings and State of New York, have invented certain new and useful Improvements in Fire and Burglar Alarms, of which the following is a specification.

10 Systems of signaling have heretofore been used in protecting houses against fire and burglary and in nearly all cases they consist of electrical devices in connection with thermostatic control in the case of fire alarms, or 15 of extensive wire systems in case of burglar alarms. In systems of this general character, a central station is required, which, as a rule, comprises a visual signal apparatus, an electric bell and releasing devices for the central apparatus, controlled from distant stations.

The object of the present invention is to reduce the electric equipment of the system to its utmost limitation for the reason, that 25 its installation is too expensive and easily disturbed and brought out of order.

The invention, in carrying out this object, consists of a central apparatus of a simple and entirely mechanical structure, operating 30 an electrical contact, which in being closed, causes a source of electric energy to operate an electric bell, while another part of the central apparatus operates a visual signal device, so that the eye as well as the ear is informed, 35 should any disturbance of the character specified, have taken place at any part of the system, distant from the central station.

The system further comprises a net of combustible threads, one for each room or set of 40 rooms of the building to be protected and extending to the central station, these threads are normally held in a tightened condition by a spring controlled rotatable disk at the central station. The disks are arranged on 45 shafts having the same axis and are provided with a visual annunciator drop, indicating the number of a room or the thread leading to the same and connected to the respective disk. The springs, controlling the disks, 50 are held under tension by the tightened threads, and in case a thread is burned or cut, the corresponding disk at the central station by its partial rotation indicates where the disturbance took place, and causes the operation 55 of an electrical or other alarm clock, as heretofore stated.

Each of the threads, causing the operation of the central apparatus, may be released in different manners, either directly by being burned and its continuity so destroyed, or by 60 being cut by means of a suitable knife. In the latter case the knife itself is controlled, in turn, by similar threads, and in some of the cases the knife may be operated by destroying the continuity of its controlling thread 65 by cutting or burning, as in case of fire, or by pulling or stretching the thread and getting it out of place, as in case of protective thread netting in burglar alarms.

In the accompanying drawings, Figure 1 is 70 a diagrammatic illustration of the entire system; Fig. 2 is a front view of the central apparatus; Fig. 3 and Fig. 4 are side elevations of the device; Fig. 5 is a vertical section in the line A—A of Fig. 2; and Figs. 6 75 and 7 are details of construction of the cutting devices, located at distant stations.

The central station apparatus, illustrated in Figs. 2-5, comprises a base plate 1, supported upon legs 2, which latter are properly secured to a wall or the partition of a room, so that the apparatus is easy of access, or in place where the attention of passers by may be called to the apparatus by the ringing of the bell or gong of the same. A number of 80 bearing lugs 3 carry a corresponding number of rotatable disks 4, each of which is provided with a display part 5, showing preferably a zero mark and a mark identifying the room to which the disk by its controlling thread is 85 connected. Each disk is held against rotation in one of its directions, by a spiral spring 6, one end of which is secured to the periphery of the disk, while the other end of the same is fastened to the base plate 1. 90 Each disk shows two stops 7 and 8, for limiting its rotation within a certain degree.

A cord or string 9, of combustible material, is secured to the disk 10, and is capable of holding the spring 6 under tension. The 100 threads 9 are led to different rooms, intended to be protected by the system, over a number of rollers, such as 11 of the central apparatus, and 12 and 13 at the distant rooms. Each of the threads is furthermore secured at the 105 distant rooms in its tightened condition to a peg or other suitable device 14. A shaft 15, arranged parallel to the axis of the disks, carries a number of rigidly connected levers 16, one for each disk and capable of being 110 actuated by a pin 17, at or near the fastening point to the disk 4 of the spiral spring 6. One

end of the shaft is provided with a contact lever 18, having a contact piece of insulating material 19, the entire lever being held in its position of rest by a spiral spring 20. A pair 5 of contacts 21 and 22 are connected through a suitable source of electric energy to a gong or bell, as well known in the art. The terminals 21 and 22 consist of a contact brush 23 on one terminal and the anvil 24 on the 10 second terminal, capable of being brought in contact by means of the lever 18. The entire central station is inclosed in a box 25, having a series of windows 26, through which the display part of the disks may be in- 15 spected.

As stated hereinbefore, the cords or strings 9 of combustible material, hold the disks 4 in such a position, that the springs 6 are under tension, and the zero display may be seen 20 through the windows of the box. In order to place a number of rooms or a number of threads or strings of the same room in connection with the corresponding disk at the central station, a main thread or cord may be 25 led from the disk over suitable rollers to the rooms and fastened to a plug or other means, while a cutting device (Fig. 6) is located in such a manner and place that should it become released, it will cut the main thread 30 and, thereby, cause the operation of the central apparatus. This release is brought about in a way similar to the actuation of the 35 central apparatus, by means of threads 26, secured to a bell-crank 27, one arm of which is provided with a cutting edge 28, capable of cutting the thread 9, passing through a suitable hole in a support 29 of the cutter. The cutter is controlled by a blade spring 30. One end of the thread 26 is secured to a suitable 40 plug, so as to hold the spring 30 under tension.

Fig. 7 illustrates a cutting device, which, in contra distinction to the device illustrated in Fig. 6, is operated by pulling the 45 string 26, instead of releasing the pull. For this purpose the bell crank 31, to which the string 26 is secured, is provided with a notch 32, normally holding a pin 33 of the cutting lever 34. The bell crank 31 is held under the 50 tension of the spiral spring 35, while the cutting lever 34 under that of the blade spring 36. It is obvious that by pulling the string 26, the lever will release the pin 33, and the knife edge, under the action of the spring 36, 55 cuts the thread 9 in a similar way as the apparatus illustrated in Fig. 6. When one of

the main threads, leading to the central station, is severed, the spring 6, controlling the corresponding disk, will cause a rotation of the same and the display in one of the windows of the central apparatus, indicating the room in which the cord was cut or severed, while the pin 17 in coöperation with the lever 16 causes contact between the terminal spring 23 and the anvil 24, thereby closing 60 the electric circuit and ringing the bell or gong.

The apparatus is useful for the protection against fire as well as against burglary. It is cheap of construction and easily applied to 70 the rooms of the building in which the system is to be installed, and its simplicity allows of reinstating the system to its normal condition at a minimum of expense and time. 75

As new and useful is claimed and desired to be secured by Letters Patent of the United States:—

1. A system of protection against fire and burglary, comprising a common annunciator, 80 a main set of cords or threads controlling said annunciator and leading from the same to distant points, an auxiliary set of threads or cords, and cutting devices at points of said main set and controlled by said auxiliary 85 set.

2. An annunciator, comprising in combination, a series of rotatable disks, means connected to said disks and leading to distant points for controlling said disks, means for 90 tending to displace said disks, an electric circuit containing a source of energy and a translating device, and a contact device controlled by said disks and adapted to close said electric circuit on the displacement of 95 either of the disks.

3. A system of protection against fire and burglary, comprising a common annunciator, a main set of cords or threads controlling 100 said annunciator and leading from the same to distant points, an auxiliary set of threads or cords, cutting devices at points of said main set and controlled by said auxiliary set, and a bell circuit controlled by said annunciator for indicating the operation thereof. 105

Signed at New York, in the county of New York and State of New York, this 8th day of September, A. D. 1906.

BERNARD STAUB.
